CLAIM

The ornamental design for an extruded wiper blade, as shown and described.

DESCRIPTION

FIG. 1 is a perspective view of an extruded wiper blade showing our new design, the blade is shown broken away in the middle to indicate indeterminate length;

FIG. 2 is a front elevational view thereof, the rear view is identical;

FIG. 3 is a top view thereof;

FIG. 4 is a side view thereof, the opposite side is identical; and,

FIG. 5 is a bottom view thereof.

The blade is shown broken away in FIGS. 3-5 to indicate indeterminate length.
